Primary Examiner — Cathron C Brooks*Assistant Examiner* — Sharon S Oum(74) *Attorney, Agent, or Firm* — Muncey, Geissler, Olds & Lowe, P.C.x(57) **CLAIM**

The ornamental design for a ceiling fan housing with light, as shown and described.

DESCRIPTION

FIG. 1 is a perspective view of the present design;

FIG. 2 is a front view of the present design;

FIG. 3 is a rear view of the present design;

FIG. 4 is a left side view of the present design;

FIG. 5 is a right side view of the present design;

FIG. 6 is a top view of the present design; and,

FIG. 7 is a bottom view of the present design.

The broken lines showing of portions of the ceiling fan housing with light form no part of the claimed design.

1 Claim, 7 Drawing Sheets(56)
